INDICATING CONTROL LEVER OR THE LIKE

Harrison M. Dean, 205 N. 31st Ave.,
Yakima, Wash. 98902

Filed June 1, 1971, Ser. No. 149,091

Term of patent 14 years

Int. Cl. D15—99

U.S. Cl. D8—107

Fig. 1.

Fig. 2.

Fig. 3.

FIGS. 1, 2 and 3 are isometric, top and side views, respectively, of an indicating control lever or the like, showing the new design.

The dot-dash lines in FIGS. 1 and 3 depict a typical mounting of the lever, shown for illustrative purposes only, and are not a part of the claimed design.

The characteristic features of my design reside particularly in the appearance of a spherical knob having an opaque lower portion and a transparent upper portion through which can be seen indicating elements, as best seen in FIG. 1.

I claim:

The ornamental design for an indicating control lever or the like, as shown and described.
